Dec 15 1879

Frederick S. Otis, of Brooklyn, N. Y.
Letters Patent No. 1579, dated May 13, 1862.

To schedule referred to in these Letters Patent and making part of the same.

To all whom it may concern:

Be it known that I, F. S. Otis, of Brooklyn, in the County of Kings and State of New York, have produced a new and ornamental Design for Block Base Fronts, and I do hereby declare that the following is

Dec 1579

a full, clear and exact description of the same, reference being had to the accompanying drawing forming a part of this specification.

The drawing represents a face view of my invention.

The principal feature of this design consists in an arbor of grapevines and rose bushes which rise from low round posts at the extreme ends of the design, the space between said posts being ornamented by two branches of roses and rose leaves and by a central circular wreath covered over by an arabesque, the whole being arranged and combined as will be hereinafter more fully described.

The base A, which supports the entire structure consists of a flat plate with a curved edge, and this base supports the posts B. Each post consists of three distinct parts, the base a, the shaft b, and the capital c. The bases a, are ornamented by mouldings a', a'', and the capitals c, by mouldings c', c'', and from these posts rises the arbor c.

The two sides of this arbor are precisely alike, each side being separated from the intervening open space by an arabesque d, which rises up to about the middle of the height of the arbor. The arbor, itself is formed of grapevines e, and rose bushes f, and besides the leaves the branches of the rose bushes and the tendrils of the grapevines it is ornamented on each side by two roses f', and also three grape leaves e', and grapes e''. The roses f', are arranged on the extreme edges of the arbor one above the other, and one of the grapes e'', is in line with and on the inside of the upper rose f', and it is partially covered over by one of the grape leaves e'. Two of these leaves are on the extreme edges of the arbor close over the roses f', and the upper leaf partially covers that one below it. The inner or third grape leaf is on the inside of the arbor and it partially covers the grapes e'', both below and above.

The upper centre of the arbor is ornamented by an arabesque g, and several leaves h, which are surrounded by three roses i.

The space between the posts B, is ornamented by two rose branches j, extending upward from a leaf k, which covers over or apparently retains the butt ends of said branches. The upper ends of these branches

3

are ornamented by buds *j'*, and open flowers *j''*, are seen at or near the middle of their length. Said open space is covered over by an arabesque *l*, and its central part is ornamented by a circular wreath *m*, the whole being arranged and combined so as to produce a very rich and handsome design.

Having thus fully described my design what I claim as new and desire to secure by Letters Patent, is -

The arbor *C*, consisting of rose bushes *f*, grape vines *e*, roses *f*, grape leaves *e'*, and grapes *e''*, arabesques *l*, and *q*, and roses *i*, as shown and described, also the posts *B*, rose branches *j*, flowers *j''* and buds *j'*, circular wreath *m*, and arabesque *l*, all as specified:

Witnesses,

Wm. Stoll.

W. Hauff.
